UNITED STATES PATENT OFFICE.

EDWIN L. UPSON, OF HARTFORD, CONNECTICUT, ASSIGNOR TO THE
PRATT & CADY COMPANY, OF SAME PLACE.

GATE-VALVE.

SPECIFICATION forming part of Letters Patent No. 623,265, dated April 18, 1899.

Application filed October 1, 1898. Serial No. 692,413. (No model.)

To all whom it may concern:

Be it known that I, EDWIN L. UPSON, a citizen of the United States, residing at Hartford, in the county of Hartford and State of Connecticut, have invented certain new and useful Improvements in Gate-Valves, of which the following is a specification.

This invention relates to a straightway gate-valve in which the gate is formed of independent disks that when the valve is closed are forced from each other against the seats by wedges located on the sides of the gate-chamber.

The object of the invention is the production of a valve of this nature which is very simple to manufacture, exceedingly cheap in construction, quite durable in use, efficient in service, and easily repairable when necessary.

The body of the valve that is illustrated in the accompanying drawings as embodying the invention is cast to shape with recessed lugs on the sides of the gate-chamber. These lugs loosely retain tapering blocks or wedges that can be cast to shape and quickly located in place. The cast disks, which are loosely engaged by a cast opening and closing spindle-yoke, are provided with inclined surfaces which coöperate with the tapering surfaces of the loose wedges held by the lugs that the disks are forced apart and caused to very tightly fit against the seats when the gate is closed. As the wedges are loosely retained in position and as the disks are independent of each other and are loosely engaged by the spindle-yoke, such a self-adjustment occurs when the gate is closed that although all of the parts may be cast to shape in a cheap manner and assembled without machine finish or fitting there will be no leakage when used with fluid under high pressures.

Figure 1 of the views shows a transverse section of the body, a side elevation of the spindle-yoke, and the back of one of the disks in closed position, one of the loose wedges being omitted. Fig. 2 shows a longitudinal section of the body, the disks, and the spindle-yoke. Fig. 3 shows a longitudinal section of the body and one of the disks. Fig. 4 shows a horizontal section of the body, disks, and spindle-yoke. Fig. 5 is a view of the inside

face of one of the wedges. Fig. 6 is an edge view of the spindle-yoke, and Fig. 7 is a view of the edge of one of the gate-disks.

The body 1 of the valve may be cast to 55 shape of iron, brass, or any other suitable metal, with screw-threaded or flanged ends for the attachment of the pipes of the system in which it is employed and for the attachment of the bonnet. In the fluidway rings 2 are 60 preferably screwed to form the seats around the ports. These rings may be formed of brass or other soft metal that is suitable for forming good seats. The only machining that is required in the body is that which is necessary for screwing these seat-rings to place. When the body is cast, lugs 3 with recesses 65 back of them are formed on the side walls of the gate-chamber. Tapering blocks or wedges 4, that may be cast with ends shaped to loosely 70 fit into the recesses, are supported by these lugs. The ends of the wedges are preferably thinner than the bodies and so rest in the recesses that the wedges cannot fall inwardly. The smaller ends of the wedges are preferably 75 provided with prongs 5, arranged to be bent into notches in the outer lugs, and the larger ends of the wedges preferably have prongs 6 that can be bent on each side of the inner lugs. When the wedges are in position, these 80 prongs are bent over, so as to retain the wedges from sidewise displacement. The wedges have limited movements when in place, so that they may adjust themselves 85 freely, the prongs only restraining them from displacement.

The disks 7, which form the gate, are substantially circular pieces of cast-iron or other suitable metal. In the form shown the seating-faces are formed of soft metal cast upon 90 the outer faces of the disks and held in place by flowing the soft metal into undercut grooves. On the inner faces of the disks, so as to coöperate with the tapering surfaces of the wedges, are inclined surfaces 9. When 95 the disks are moved inwardly, these inclines engage the wedges in such manner that the disks are forced from each other and the seating-faces caused to press tightly against the faces of the seat-rings in the body.

In the center of the inner faces of the disks are recesses 10, and loosely extending into

these are the hubs 11, that project from the yoke 12, which has a socket that is threaded to receive the threaded handle-spindle. Lugs 13 may be provided on the inner faces of the disks 5 to limit the movements of the disks edgewise with relation to each other and to the spindle-yoke. When the spindle-yoke is moved inwardly by the turning of the handle-spindle, the disks are forced toward the inner end of the 10 gate-chamber, but they are free to move in all other directions, for the circular hubs of the spindle-yoke only loosely engage the walls of the recesses in the inner faces of the disks. As the disks move toward the inner end of 15 the gate-chamber the engagement of the inclines on their inner faces with the tapering edges of the wedges forces them from each other until their seating-faces make close contact with the faces of the seat-rings.

20 The wedges are loose, and should one of the disks be in advance of the other or should one side of one be lower than that side of the other or should the wedges or the inclines be imperfectly formed or untrue the wedges will 25 move and adjust themselves to all irregularities of this nature, so that the disks will be surely forced tightly against the seat-rings. If one of the disks becomes more worn than the other or if the inclines on the disks or the 30 edges of the loose wedges wear unevenly, the wedges will adjust themselves, so that both of the disks will close tightly.

With this invention, although the disks are forced from each other by wedges on the side 35 walls of the body, the seating of each disk depends upon the other—that is, they mutually act to make tight joints and the wedges accommodate themselves and occupy intermediate positions.

40 The parts of this valve can all be formed in a foundry. There are no intricate shapes, no special fitting or machinery is required, and the parts can be assembled quickly without liability of improper arrangement. All 45 of the parts are durable. Either of the disks can be removed and repaired or the disks can be reversed if either should be subject to more wear than the other.

This valve can be located and will success- 50 fully operate in any position without danger that the parts will become disarranged.

I claim as my invention—

1. A valve having a body, a gate formed of independent sections movable together inwardly and outwardly in the gate-chamber in the body, lugs formed on opposite walls in the 55 gate-chamber, and wedges loosely supported by the lugs on opposite sides of the gate-chamber so as to, by contact with inclines on the 60 edges of the backs of the gate-sections, force

the gate-sections from each other as the valve is being shut, substantially as specified.

2. A valve having a body, a gate formed of independent sections movable together inwardly and outwardly in the gate-chamber in 65 the body, a pair of lugs cast integral with opposite walls of the gate-chamber, and wedges loosely supported by the lugs on opposite sides of the gate-chamber and provided with prongs that prevent the removal of the wedges from 70 the lugs without interfering with their movement, said wedges being arranged so as to, by contact with inclines on the edges of the backs of the gate-sections, force the gate-sections from each other as the valve is being shut, 75 substantially as specified.

3. A valve having a body, a gate formed of independent sections movable inwardly and outwardly in the gate-chamber in the body, wedges loosely supported by the side walls of 80 the gate-chamber and arranged to adjust themselves and force the gate-sections from each other when the valve is being shut, and a spindle-yoke loosely connected with the gate-sections, substantially as specified. 85

4. A valve having a body, a gate formed of independent sections movable inwardly and outwardly in the gate-chamber in the body, said sections having inclines on and recesses in their back faces, wedges loosely supported 90 by the side walls of the gate-chamber and arranged to adjust themselves and force the gate-sections from each other when the valve is being shut, and a spindle-yoke with hubs loosely projecting into the recesses in the 95 back faces of the disks, said yoke being provided with a threaded socket for the reception of the threaded handle-spindle, substantially as specified.

5. A valve having a body, a gate formed of 100 independent sections movable inwardly and outwardly in the gate-chamber in the body, said sections having inclines on and circular recesses in their back faces and annular seat- 105 ing-rings on their front faces, wedges sup- 110 ported by lugs formed on the side walls of the gate-chamber, said wedges being loosely retained in position and arranged to adjust themselves and force the gate-sections from each other when the valve is being shut, and 115 a spindle-yoke with circular hubs loosely projecting into the recesses in the back faces of the disks, said yoke being provided with a threaded socket for the reception of the threaded handle-spindle, substantially as specified.

EDWIN L. UPSON.
